Gregory J. Foster, Chicago, IL (US)

(57)

CLAIM

(73) Assignee: **Fellowes, Inc.**, Itasca, IL (US)

The ornamental design for an organizing tray, for attachment to a wall, such as a cubicle wall, as shown and described.

(**) Term: **14 Years**

DESCRIPTION

(21) Appl. No.: **29/163,464**

A portion of the disclosure of this patent document contains material to which a claim for copyright is made. The copyright owner has no objection to the facsimile reproduction of the patent document or the patent disclosure, as it appears in the Patent and Trademark Office patent file or records, but reserves all other copyrights whatsoever.

(22) Filed: **Jul. 8, 2002**

FIG. 1 is a perspective view of an organizing tray for attachment to a wall, such as a cubicle wall embodying our new design;

(51) LOC (7) Cl. **19-02**

FIG. 2 is a front elevational view thereof;

(52) U.S. Cl. **D19/75; D19/77; D19/90**

FIG. 3 is a left side elevational view, it being understood that the right side view is essentially a mirror image of the left;

(58) Field of Search D19/65, 75, 77,

FIG. 4 is a top plan view thereof; and,

D19/78, 81-85, 86, 90, 91, 99, 100; 206/214,
224, 371; 211/69.1-69.9, 88.01, 42, 45,

FIG. 5 is a rear elevational view thereof.

46, 10, 11, 50; D6/553, 449, 567; 229/117.18

The structure depicted by means of broken lines in FIGS. 1 and 4 has been shown for illustrative purposes only and forms no part of the claimed design.
